UNITED STATES PATENT OFFICE.

JOSEPH ALBERS, OF WELLS, OREGON.

GATE.

SPECIFICATION forming part of Letters Patent No. 395,804, dated January 8, 1889.

Application filed July 13, 1888. Serial No. 279,884. (No model.)

To all whom it may concern:

Be it known that I, JOSEPH ALBERS, a citizen of the United States, residing at Wells, in the county of Benton and State of Oregon, 5 have invented a new and useful Improvement in Gates, of which the following is a specification.

This invention contemplates certain improvements in gates, more especially for the 10 passage of teams without requiring the dismounting of the driver, having for its object to provide for the ready opening and closing of the gates and the simultaneous unfastening or unlatching and opening of the same, 15 as also automatically to secure the gates in their open position and to effect at one operation the release of the gates and the closing thereof; and the nature of the invention consists of mechanism for carrying out these 20 ends, substantially as hereinafter fully described, and pointed out in the claims.

In the accompanying drawings, Figure 1 is a perspective view of my improved gate. Fig. 2 is a plan view of the same, partly in section; 25 and Figs. 3, 4, and 5 are enlarged detail sectional views thereof.

In the application of my invention I employ, preferably, two gates, A A, of the construction shown, of which the hinging-posts 30 *a a* are suitably pivoted in the base or sill and overhead pieces *b b'* of a frame, B, braced in position. The gates A A are provided at their forward edges one with an edgewise-disposed or vertical beveled plate, *c*, and the 35 other with a keeper-plate, *c'*, to the forward ends of which are secured springs or "snaps" *c² c²'*. These springs or snaps are arranged in alignment with each other and project or extend outwardly and obliquely from the plate, 40 their free ends standing opposite to each other and a short distance apart, to receive between them the beveled edge of the plate *c* to effect the holding together of the gates thereat.

45 C C are grooved disks or pulleys applied to the pivots at the upper ends of the hinging or pivoting posts *a* of the gates A A, and are provided upon their peripheries in the grooves with projections or stops *d d*, disposed to prevent the slipping or displacement of the 50 chains or lines, presently referred to.

About at the center of the overhead piece *b'* of the frame B is an opening or passage, *b²*, immediately in alignment with which, upon the under side of the said piece, are secured 55 and disposed two spring-plates or catches, *d' d'*. The catches or plates *d' d'* are bowed or inclined downward, their free ends standing a short distance apart and opposite to each other, to receive between them bevel-ended 60 studs or plates *d² d²*, applied to the upper ends of the forward end gate-bars, *d³ d³*.

D D are propping or holding levers arranged above the overhead piece *b'* of the frame B, and having a common pivotal connection with 65 one of two upright brackets or frame-like supports, *e*, secured or mortised into the upper side of the said piece. This pivotal connection is effected by the passage of a pivot-bolt, *e'*, through apertures in said propping or holding levers and said bracket or frame-like support *e*. The propping or holding levers D D are connected, by means of rigid links or short rods *f f*, with the spring-plates or catches *d' d'*, by means of which the action of the spring- 70 plates or catches is further utilized to hold the propping or holding levers in their normal inclined position, as also to effect the disengagement of the catches or spring-plates as the operating-levers, referred to farther on, 75 are actuated, so as to open the gates. The propping or holding levers D D are provided with pulleys *g g*—one disposed in a slot or opening, *g'*, in each lever. To the upper side of the overhead piece *b'* of the frame B is 80 fastened, intermediately of and standing partly in alignment with each of the propping or holding levers D, a beveled cleat, *h*, which serves as a stop to limit the downward and outward movement of the latter as their inner 85 ends are moved upward, as will more fully appear hereinafter.

E E are two chains or lines operating and applied one to each pulley or grooved disk C of the gates. Those portions of the two lines 90 or chains E E upon the same side are passed under one pulley *g* of one of the propping-levers D and have their ends connected together and looped upon a hook, *g²*, of one of two hand-levers, F F, suitably pivoted in the 95 frame-like supports or brackets *e*. The opposite portions of the lines or chains E E are

passed under the pulley g of the other prop-
ping-lever D and have their ends connected
and looped upon the hook g^2 of the opposite
hand-lever F. This effects a connection be-
5 tween and permits of the actuation of the
gate-pulleys, the props or levers, and the gate-
holding catches by means of the hand-levers.
In order to effect synchronous movement of
10 the gate-pulleys C C, they are connected to-
gether by a connecting-rod, i , and crank arms
or links $i^2 i^2$, which latter are fixed to said pul-
leys and to the ends of said connecting-rod.
The connecting-rod i is notched, as at $i^2 i^2$,

15 to permit of the engagement therewith of the
free or upper ends of the propping or hold-
ing levers D D when the gates are open.

In operation it will be seen that by depressing
the outer end of either hand-lever F the
chain or line E, connected therewith, will be
20 drawn upon, which will simultaneously ele-
vate or disengage the connected spring-plate
or catch d' from the beveled plates or studs
 $d^2 d^2$ of the gates and rotate the pulleys C C,
which will swing open the gates, the opening
25 action of the gate automatically effecting the
disengagement of the plate c from the spring-
plates or snaps $c^2 c^2$ at the forward edges
of the gates. Upon the gates attaining their
maximum extent of opening movement and
30 the release of the hand-levers the connecting-
rod i will have been moved obliquely across
the piece b' of the gate-supporting frame B
into position to permit of the engagement with
one of its notches i^2 of the coincident one of
35 the propping or holding levers D, which will
thus prop or secure the gates in their open po-
sition.

In closing the gates, which is effected by the
depression of the opposite hand-lever after
40 the passage of the team, it will be seen that
simultaneously with such movement of said
hand-lever the coincident propping or holding
lever will be depressed or disengaged from
the engaging-notch of the connecting-rod by
45 the upward pull of the pulley-operating line
or chain upon the coincident spring-plate or
catch d , thus effecting the releasing of the
gates from the holding levers or props and the
closing or shutting of the gates at one opera-
50 tion.

Having thus fully described my invention,
what I claim, and desire to secure by Letters
Patent, is—

1. The combination, with a pair of pivoted
55 gates, of pivoted opening-levers, connections
between said levers and the pivots of the gates,
a rod connected to the pivots of the gates, and
holding-levers operated by the pivoted levers
and engaging the said connecting-rod, sub-
60 stantially as described.

2. The combination, with a pair of pivoted
gates, of disks on the pivots of the gates, piv-
oted operating-levers, flexible connections be-

tween the said levers and disks, and pivoted
holding-levers connected to the flexible con- 65
nections, substantially as described.

3. The combination, with a pair of pivoted
gates, of disks secured to the pivots of the
gates, a rod having its ends connected to the
disks, pivoted operating-levers, pivoted hold- 70
ing-levers for engaging the said connecting-
rod provided with pulleys, and cords or chains
connected to the said disks passing around
the pulleys of the holding-levers and con-
nected to the operating-levers, substantially 75
as described.

4. The combination, with a pair of pivoted
gates, of disks secured to the pivots of the
said gates, a rod having its ends eccentrically
connected to the disks, holding-levers for en- 80
gaging the rod provided with pulleys, ropes
or chains passing around the pulleys of the
holding-levers and connected to the operating-
levers, and disks, spring-catches, and a
connection between the said holding-levers 85
and catches, substantially as herein shown
and described.

5. The combination of a pair of pivoted
gates with a notched rod connecting pulleys
on the gate, pivoting or hinging posts, and a 90
propping or holding lever engaging said rod,
substantially as set forth.

6. The combination, with a pair of pivoted
gates, of a notched rod connecting gate-oper-
ating pulleys, spring gate-locking plates or 95
catches, and the propping or holding lever
connecting with the spring plates or catches
and engaging the said rod, substantially as
described.

7. The combination, with a pair of pivoted 100
gates and their operating-levers, of the gate-
pulley-operating lines or chains, a rod con-
necting the gate-pulleys, and the holding or
propping levers limited in their outward
105 downward movement by a stop suitably dis-
posed and carrying pulleys, said lines or
chains connecting the gate-pulleys and the
operating-levers and passing up in contact
with the pulleys carried by said holding or
propping levers, substantially as specified. 110

8. The combination, with a pair of pivoted
gates carrying pulleys at the upper ends of
their pivoting or hinging posts and bevel-
ended plates or studs at the upper ends of 115
their forward edges, of chains or lines applied
to and operating said pulleys and applied to
operating-levers, bowed or curved spring
plates or catches, and the holding or prop-
ping levers connected to said spring plates or 120
catches, said lines or chains passing up in con-
tact with pulleys hung in said holding or
propping levers, substantially as set forth.
